FLUID PRESSURE ASSEMBLY

Benjamin P. Baker, Turtle Creek, Erling Frisch and Howard M. Wilcox, Pittsburgh, Pa., assignors to Westinghouse Electric Corporation, East Pittsburgh, Pa., a corporation of Pennsylvania

Application February 3, 1949, Serial No. 74,407

4 Claims. (Cl. 200—148)

1

Our invention relates to compressed-air circuit-breakers, and it has particular relation to a yieldable assembly-means for holding the various parts of the single-column interrupter-structure together in substantially air-tight abutting-engagement with each other, while providing for sudden and unequal thermal expansions and contractions of the various parts. While our invention is mainly directed to such a circuit-breaker structure, the general principles thereof are applicable also to other assemblies and structures, where similar problems are encountered.

The principal object of our invention is to provide a captivated-spring assembly, for co-operating with a plurality of tie-rods for holding the assembled parts together.

In a specific circuit-breaker application, our invention relates to the blast-tube and interrupter-assembly part of a compressed-gas circuit interrupter, which is covered in a copending application of Benjamin P. Baker, Erling Frisch, Wayne S. Aspey and John B. MacNeill, Serial No. 74,406, filed February 3, 1949. There is included the general combination of a compressed-air tank, with an insulating blast-tube extending upwardly from the top of the tank, an extension of the blast tube inside of the tank, a blast-valve which is accessible and operable from the bottom side of the tank and which normally closes the bottom of the blast-tube extension within the tank, and a suitable air-blast interrupter-assembly mounted on top of the blast-tube so as to be physically supported by the blast-tube, as well as being insulated from ground by the blast-tube.

With the foregoing and other objects in view, our invention consists in the combinations, assemblies, systems, structures, parts, and methods of design and operation, hereinafter described and claimed, and illustrated in the accompanying drawing, wherein Fig. 1 is a side elevational view, partly in section, and largely diagrammatic, not to scale, indicating the general principles of our invention as applied to a single-pole assembly, and Fig. 2 is a detailed elevational view, partly in longitudinal section, showing our novel captivated-spring assembly-means for holding the various interrupter-parts together and in air-tight mechanical connection with the top of the blast-tube.

Figure 1 shows a single pole of a compressed-air breaker-assembly embodying our invention. It is to be understood, however, that our invention is often or usually applied to a three-phase

2

power-system, in which case each pole would consist of the structure as shown in Fig. 1, except that a single operating-mechanism may be used for gang-operation of all three poles, and possibly also a single compressed-air tank might be used for supporting the blast-tubes of all three poles.

Each pole of the breaker preferably has its own compressed-air tank or reservoir 1, which is made of steel, and which serves also as a supporting-structure for the rest of the assembly. We provide a vertically disposed, insulating, blast-tube 2 which extends upwardly above the top of the tank and is supported by the tank. Inside of the tank, there is a vertically disposed tube-means 3, which is in alignment, and air-flow communication, with the bottom of the blast-tube 2, so that said internal tube-means 3 serves, in effect, as a blast-tube extension which extends downwardly, within the tank, to a point near, but spaced from, the bottom of the tank, as indicated at 4. Physically, this blast-tube extension, inside of the tank, could be a part of the insulating blast-tube 2, which could be made long enough to extend down to the point 4 near the bottom of the tank, but actually, it is more convenient to make the internal tube-means 3 out of iron or steel which is welded or otherwise properly secured within the tank 1. Also, in a practical construction, it would be possible for the internal tube-means 3 to comprise the top part of an internal tube which physically extends from the top of the tank all the way down to the bottom of the tank, but which is provided with side-openings at the effective tube-bottom 4, so that said tube-means would be intact, as a tube, only above the point 4.

Disposed within the tank 1, under the bottom 4 of the tube-means 3, is a blast-valve 5, which is accessible and operable from the bottom of the tank. The blast-valve 5 is preferably a differential-pressure valve, having a vertically movable inverted-cup member 6, which is pressed up, by a compression-spring 7, into tight seating-engagement with the bottom end 4 of the tube-means 3. The compression-spring 7 acts as a weak closing spring, which does not exert enough pressure to close the valve against the air-pressure in the tank 1, which may be at something of the order of 250 pounds per square inch. Normally, the blast-valve 5 is held closed by being supplied, from underneath, with air at the same pressure as the air in the tank 1, as by means of a valve-controlling pipe

8, which is in communication with the underside of the movable inverted cup 6, so that the valve is thus held closed. The valve is opened by releasing the air-pressure which is applied by the valve-controlling pipe 8, thus permitting the air-pressure within the tank to push down the inverted cup 6, thus permitting air to rush, in large quantities, upwardly through the internal tube-means 3 and through the insulating blast-tube 2.

On top of the insulating blast-tube 2, we mount a single-column interrupter-assembly 10, which is preferably supported in a vertical position, in alignment with the blast-tube 2, and which is physically supported solely, or substantially entirely, by the blast-tube, so as to be electrically insulated from ground by said blast-tube. This single-column interrupter-assembly comprises a plurality of vertically aligned, self-opening, longitudinal-blast interrupter-gap devices 11 and 12, two such gap-devices being used on a 69-kilovolt breaker as illustrated. These gap-devices 11 and 12 are electrically connected in series, so that the current-flow, in the normal closed position of the breaker, is from the top 13 of the interrupter-assembly 10 to the bottom 14 thereof, a suitable line-terminal 15 being provided at the top 13. Each interrupter-gap device 11 and 12 comprises a stationary contact-member 11S or 12S, as the case may be, and a vertically movable contact-member 11M or 12M, as the case may be. The two movable contact-members 11M and 12M are normally biased towards closed position by means of biasing-springs 11B and 12B respectively.

In the construction which is very much preferred, the first stationary contact-member 11S is at the bottom 14 of the interrupter-assembly 10, and is integrally or electrically united with a lower exhaust-chamber 16, which is made of metal. The stationary contact-member 11S is hollow, and extends down into the lower exhaust-chamber 16, as shown at 16'.

In the preferred construction, the two movable contact-members 11M and 12M are mounted within a metallic moving-contact assembly or housing 17 which is in the form of two concentric cylinders, namely an inner cylinder 17i and an outer cylinder 17o, so as to provide an annular space 17s between these cylinders, through which the air-blast may pass.

The moving-contact housing 17 is vertically spaced from the lower exhaust-chamber 16 by means of an insulating tube 18, which supports the outer cylinder 17o, and which is larger than the lower stationary contact-member 11S, so as to provide an annular space 18s therearound, through which the air-blast may pass. In order to guide the air-blast from the blast-tube 2 into the annular space 18s, the lower exhaust-chamber 16 is provided with a funnel-like air-guiding duct 19, which is spaced from the lower end 16' of the lower stationary contact-member 11S, so as to provide an annular space 19s through which the air-blast may pass, in moving upwardly from the blast-tube 2 into the annular space 18s.

The upper stationary contact-member 12S is integrally or electrically united with an upper exhaust-chamber 20, which is similar to the lower exhaust-chamber 16, except that it lacks the funnel or duct 19 for carrying the blast-air upwardly on through the upper exhaust-chamber 20. The upper stationary contact-member 12S is likewise of hollow construction, and its upper

end is in communication with the space within the upper exhaust-chamber 20. This upper exhaust-chamber 20 is supported on the top end of an insulating tube 21, which is similar to the tube 18, except that the lower end of the top insulating tube 21 rests on top of the outer cylinder 17o of the moving-contact housing 17. This upper insulating tube 21 is also larger than the upper stationary contact-member 12S, so as to provide an annular space 21s which forms a closed upper end for the blast-air, as this blast initially moves upwardly through the interrupter-assembly 10.

In the construction which is very much preferred, as illustrated, the upper end of the lower stationary contact-member 11S, and the lower end of the upper stationary contact-member 12S are each provided with a centrally disposed orifice 22, which is normally closed by the cooperating movable contact-member 11M or 12M, as the case may be. The configuration of these movable contact-members 11M and 12M is such that the pressure of the blast-air operates on these movable contact-members 11M and 12M to press them back away from their respective stationary contact-members 11S and 12S, thus making the gap-devices 11 and 12 self-opening, that is, making them open automatically, by themselves, as soon as a sufficient gas-pressure is built up in the spaces around them, without requiring any other device, not a part of the moving-contact assembly 17, for causing a separating-movement of the movable contact-members 11M or 12M. This opening-movement of the movable contact-members 11M and 12M draws arcs between said members and their associated stationary contact-members 11S and 12S, respectively, thus initiating a circuit-interrupting operation of the breaker.

As soon as each movable contact-member 11M or 12M moves away from its normal contact-making engagement with the end of its associated stationary contact-member 11S or 12S, as the case may be, it uncovers the orifice 22 in the hollow stationary contact-member 11S or 12S, thus permitting a blast of air to move longitudinally, or in a vertical direction, through the orifice 22 and thence through the hollow stationary contact-member 11S or 12S, and thus acting powerfully to extinguish the arc between the movable and stationary contact-members. The upper end of the hollow upper stationary contact-member 12S dumps its air directly into the upper exhaust-chamber 20, and the lower end 55 of the lower hollow stationary contact-member 11S exhausts its blast of air into the lower exhaust-chamber 16 by means of a plurality of tubular openings 23, which pass through the lower end 16' of the hollow lower stationary contact-member 11S, and also through the funnel or duct 19 in the lower exhaust-chamber 16.

These upper and lower exhaust-chambers 20 and 16 thus provide an expansion-space in which the longitudinally moving air-blasts within the two stationary contact-members 11S and 12S may accumulate during the brief time which is required for a complete circuit-interruption. It may take the blast something like $\frac{1}{4}$ cycle, (assuming a 60-cycle line), before the arcing-contacts begin to separate, and then a time something like $\frac{3}{4}$ cycle for the maximum contact-separation to be achieved. Then the arc may hang on for an additional time which may be slightly longer than the longest current-flow period or half-cycle which could be expected under

asymmetric-wave conditions. It is desirable for the arc to be interrupted at the first important current-zero, (or sometimes possibly the second one), after full contact-separation has been achieved, disregarding, (as unimportant from an arc-interrupting standpoint), any current-zero which may occur very soon after full contact-separation is obtained. Then it is desirable to prevent a restriking of the arc on the next half-cycle, and to this end it is necessary to have a large quantity of air-movement, a high air-velocity, high turbulence, and cooling, or a combination of these factors. And then, in subsequent half-cycles, it is desirable to continue to have a sufficient dielectric strength of the air in the arcing-gap, so as to prevent any subsequent arc-restriking, and for this purpose, the air-pressure of the once-deionized and cooled gap-air is of service in providing dielectric strength to prevent a later breakdown of the gap.

Our upper and lower exhaust-chambers 20 and 16 provide the gas-pressure in the gap-space. The initial blast must be maintained until at least the first (or second) important current-zero after full gap-separation has been reached, but when the back-pressure in these exhaust-chambers reaches as much as something like 50% of the pressure at the high-pressure side of the orifice or arcing-gap, the blast no longer travels at approximately the speed of sound, but begins to slow down. The size of the exhaust-chambers 16 and 20 should be such, therefore, that this 50% air pressure should not be built up therein until after the above-mentioned important current-zero. To provide a reasonable factor of safety, we prefer to have this 50% pressure occur within about 2½ cycles after the opening of the blast-valve 5.

However, it is important that these exhaust-chambers 16 and 20 should be present, and that they should develop an important back-pressure after said period of 2½ cycles or the like, and it is important that these exhaust-chambers should be able to hold their back-pressures for a few cycles, or until a serially connected isolating-switch 26 can be opened, as will subsequently be described. During this time, when a substantial back-pressure is being held in the exhaust-chambers 16 and 20, the blast-valve 5 must be kept open, as will readily be understood.

The air which accumulates in the two exhaust-chambers 16 and 20 is cooled, in these chambers, and is slowly dissipated to the atmosphere, through suitable exhaust-openings 24, which are provided in each of the exhaust-chambers 16 and 20, and which may be provided with any desirable muffling or sound-deadening or flame-extinguishing means (not shown), as is well understood in the compressed-air circuit-breaker art.

Since the movable contact-members 11M and 12M are opened by the air-pressure which is exerted by a large body of fast-moving air, in a blast which moves at a velocity approaching the velocity of sound, it is impractical to sustain such a large movement or blast of air for any considerable length of time. It is necessary, therefore, to close the blast-valve 5 very quickly after it is opened, so as to conserve the high-pressure air or gas which is stored in the tank or reservoir 1. Consequently, after a circuit-interrupting operation by the isolating-switch 26, the blast-valve 5 is reclosed, and therefore the two movable contact-members 11M and 12M close again into contact with their respective stationary contact-members 11S and 12S, so that these contact-members thereafter remain closed throughout the

time when the circuit should remain interrupted. It is necessary, therefore, as in the case of previously known self-opening, longitudinal-blast, orifice-type circuit-breakers, to provide the previously mentioned isolating-switch 26 which is electrically connected in series with the interrupter-assembly 10.

We also provide a second vertically disposed insulating column 21, which is spaced from the blast-tube 2, and which also extends upwardly above the top of the tank 1, so that it is supported by the tank, although it is not in pneumatic communication with the air within the tank 1. This second insulating column 21 is surmounted by a metal terminal-member 28, which is provided with a line-terminal 29, so as to provide the second line-terminal of the breaker-assembly, the first line-terminal being the terminal 15 at the top of the interrupter-assembly 10. The isolating-switch 26 is movable so as to close or open an electrical circuit between this metal terminal-member 28 at the top of the second insulating column 21, and the bottom 14 or 16 of the interrupter-assembly 10 which is mounted at the top of the insulating blast-tube 2. In the illustrated construction, the isolating switch 26 is pivotally connected to the lower exhaust-chamber 16, as indicated at 30, and its free end is movable into and out of contact with suitable contact-fingers 31 carried by the metal terminal-member 28.

It is also a feature of the type of breaker to which our invention is applicable, that an operating-mechanism is provided, as diagrammatically indicated at 33, in a location which is on, or close to, the tank 1, and which is at substantially the same electrical potential as the tank, which would normally be grounded. Thus, this operating-mechanism 33 is physically and electrically at the ground-level, which is of considerable advantage from the standpoint of the amount and size of the equipment which must be insulatedly supported, up in the air, as by the two insulating supporting-columns 2 and 21. The operating-mechanism 33 is operatively joined to the switch 26 through an insulating switch-operating rod 34, for opening and closing the isolating-switch 26.

The operating-mechanism 33 may be controlled in any desired manner, so that it will open the isolating-switch 26, and lock it open, after the completion of the arc-interruption during the opening-operation of the interrupter-assembly 10, and before the two movable contact-members 11M and 12M are spring-closed again, after a reclosure of the blast-valve 5. In the particular design illustrated, the operating-force, and the timing, for the operating-mechanism 33 are both provided by a small tube or pipe 35, which is in communication with the lower end of the insulating blast-tube 2, or the upper end of the internal tube-means 3 in the tank 1. When the blast-valve 5 first opens, the air or blast is moving upwardly very rapidly in the blast-tube 2, so that its static air-pressure is relatively small. This blast travels upwardly, at a velocity approximating the velocity of sound, until its upward movement is halted by the top of the upper annular space 21s, and then pressure begins to be built up in this blast-air space, serving first to open the two movable contact-members 11M and 12M, after which said air-pressure builds back downwardly, until the level of the top of the tank 1 is reached, at which time a sufficient air-pressure is applied, through the tube 35, to begin to initiate the operation of

the operating-mechanism 33. The inertia of the operating-mechanism 33, the insulating connecting rod 34, and the isolating-switch 26 is such that the isolating-switch 26 breaks its contact with the contact-fingers 31 after the arcs have been interrupted by the longitudinally flowing gas-blast in the two interrupter-gap devices 11 and 12.

As shown in Fig. 2, our invention relates more particularly to the assembly-means for the interrupter-parts which are mounted at the top of the blast-tube 2. It will be noted that this interrupter-assembly comprises a number of separate hollow parts or pneumatic elements, which are stacked up, one on top of each other, and which must be firmly held together, not only to afford a structure having the adequate mechanical strength and stability, but also to enable the abutting-joints between the several parts to withstand the air-pressure, of the order of 250 pounds per square inch, of the compressed-air blast without substantial air-leakage, while at the same time providing for considerable and unequal thermal expansions and contractions.

Our novel assembly-means, as shown in Fig. 2, comprises a plurality of insulating tie-rods 36, which are provided with nuts 37 for drawing the assembled parts tightly together in an axial direction. In order to provide for the necessary yieldability to admit of thermal expansions and contractions, we provide a captivated-spring head for anchoring one end of said tie-rods, said captivated-spring head comprising a movable pressure-plate 38 which is illustrated as being mounted within the upper exhaust-chamber 20, although it could obviously be disposed at either end of the vertically disposed tie-rods 36. The movable pressure-plate 38 is strongly biased, in an upward direction, by a nest of powerful compression-springs 39, which press against the underside of said pressure-plate so as to make it keep the tie-rods in tension.

The compression-springs 39 exert a rather considerable pressure on the pressure-plate 38, and it would be rather inconvenient to have to turn up the nuts 37 on the tie-rods 36 for a sufficient distance to set up the compression-springs 39 far enough to make them exert this considerable pressure, every time the assembly is put together, even though there were sufficient room, in the upper exhaust-chamber 20, for a sufficient axial threaded movement of the nuts 37 to accomplish this spring-compression.

In accordance with our present invention, therefore, we initially set up the compression-springs 39 by substantially the desired amount to provide the desired strong spring-force against the underside of the pressure-plate 38, using, for this purpose, any convenient jack or fixture (not shown) for temporarily holding the pressure-plate assembly in its compressed state. We then provide short retaining-bolts 40, or other equivalent retaining-means, for holding down the pressure-plate 38, into very nearly its fully-lowered position, with very nearly the full compression on the compression-springs 39, after which the assembly can be removed from the temporary holding-fixture (not shown).

The above-described construction provides a captivated-spring assembly, in which the compression-springs 39 are held captive, in the upper exhaust-chamber 20, by means of the retaining-bolts 40, which prevent the compression-springs 39 from raising the pressure-plate 38 sufficiently to cause the springs to lose any substantial amount of their "set" or compression. When the

parts are assembled, as shown in Fig. 2, the nuts 37 are tightened on the several tie-rods 36, and this tightening movement is continued until the tie-rods pull the pressure-plate 38 down for a certain clearance-distance below the heads of the retaining-bolts 40, as indicated at D. This provides the distance D which is available for thermal expansions, while automatically maintaining each of the tie-rods 36 in strong tension, so as to flexibly hold the parts firmly together.

The lower ends of the tie-rods 36 may be anchored in any suitable manner, which results in holding together the parts which are to be assembled. In the particular design shown in Fig. 2, the lower ends of the tie-rods are provided with heads 41 which engage the lower exhaust-chamber 16, and this lower exhaust-chamber 16 is secured to the top of the blast-tube 2 by means of a sort of mortise-joint which is provided by a clamping ring 42 which is affixed to the upper end of the insulating blast-tube 2, and which is secured to the lower end of the lower exhaust-chamber 16, as by means of bolts 43. It will be understood, of course, however, that the lower ends of the tie-rods 36 could have been anchored directly to the clamping-ring 42, if it had not been desirable to provide the semi-permanent bolted connection between the lower exhaust-chamber 16 and the top of the blast-tube 2.

Various details of the breaker-assembly, which is herein generically or broadly described and claimed, are described and claimed in more detail in other copending applications. Thus, certain improvements and novel features of the pneumatic operating-assembly, including the operating-mechanism 33, insulating switch-operating rod 34, isolating-switch 26, pneumatic controlling-means including the tube 35, and an interlocking-means (not here shown) for automatically reclosing the blast-valve 5 when the isolating-switch 26 has completed enough of its opening-movement, are shown and claimed in a copending application, Serial No. 73,516, filed January 29, 1949, by Baker and Wilcox. And finally, certain details and improvements in the interrupter-assembly 10, relating to the functional operation of this assembly, and a practical operating-form thereof, are disclosed and claimed in the aforesaid application, Serial No. 74,406, filed February 3, 1949, by Benjamin P. Baker, Erling Frisch, Wayne S. Aspey, and John B. MacNeill.

While we have described and illustrated our invention in but a single illustrative form, which is shown somewhat diagrammatically or ideally, we wish it to be understood that we are not limited to the precise form which is illustrated, as those skilled in the art could readily make various changes of substitution, omissions or additions, without departing from the essential spirit of our invention. We desire, therefore, that the appended claims shall be accorded the broadest construction consistent with their language.

We claim as our invention:

1. A fluid-pressure assembly comprising a stack of separate abutting hollow parts having a substantially fluid-tight connection therebetween, said assembly of separate abutting hollow parts being capable of withstanding a considerable internal fluid-pressure and capable of withstanding a wide range of thermal expansions, a plurality of tie-rods for drawing said parts together in an axial direction, and a captivated-spring head for said tie-rods, said captivated-spring head comprising a movable pressure-plate for keeping said tie-rods in tension, one or more

compression-springs for pressing against said pressure-plate so as to make it keep said tie-rods in tension, nuts whereby said tie-rods may be removed, and retaining-means for limiting the expansion of said compression-springs when said tie-rod nuts are loosened, whereby said compression-springs are retained under a considerable pressure.

2. A fluid-pressure assembly comprising a stack of separate abutting hollow parts having a substantially fluid-tight connection therebetween, said assembly of separate abutting hollow parts being capable of withstanding a considerable internal fluid-pressure and capable of withstanding a wide range of thermal expansions, a plurality of tie-rods for drawing said parts together in an axial direction, and a spring-head for said tie-rods, said spring-head comprising a movable pressure-plate for keeping said tie-rods in tension, one or more compression-springs for pressing against said pressure-plate so as to make it keep said tie-rods in tension, nuts whereby said tie-rods may be removed, and means, pressing on said plate, separate from said nuts, for building up a considerable pressure in said compression-springs.

3. A circuit interrupter of the compressed-gas type wherein contacts are separated and the arc drawn therebetween is extinguished by a flow of gas and wherein one or more abutting pneumatic elements are employed to effect a pneumatic connection, characterized by the combination of one or more insulating tie-rods for drawing said pneumatic elements together in an axial direction, and a captivated-spring head for said tie-rods, said captivated-spring head comprising a movable pressure-plate for keeping said tie-rods in tension, one or more compression-springs for pressing against said pressure-plate so as to make it keep said tie-rods in tension, nuts whereby said tie-rods may be removed, and retaining-means for limiting the expansion of said compression-springs when said tie-rod nuts are

loosened, whereby said compression-springs are retained under a considerable pressure.

4. A circuit interrupter of the compressed-gas type wherein contacts are separated and the arc drawn therebetween is extinguished by a flow of gas and wherein one or more abutting pneumatic elements are employed to effect a pneumatic connection, characterized by the combination of one or more insulating tie-rods for drawing said pneumatic elements together in an axial direction, and a spring-head for said tie-rods, said spring-head comprising a movable pressure-plate for keeping said tie-rods in tension, one or more compression-springs for pressing against said pressure-plate so as to make it keep said tie-rods in tension, nuts whereby said tie-rods may be removed, and means, pressing on said plate, separate from said nuts, for building up a considerable pressure in said compression-springs.
